US00D571614S

(12) **United States Design Patent**
Curtin

(10) **Patent No.:** **US D571,614 S**
(45) **Date of Patent:** **** Jun. 24, 2008**

(54) **COLLAPSIBLE BOWL**

D272,972 S 3/1984 De Coster

(75) Inventor: **Heather Curtin**, Renton, WA (US)

(Continued)

(73) Assignee: **Progressive International Corporation**,
Kent, WA (US)

FOREIGN PATENT DOCUMENTS

GB 2028675 3/1980

(**) Term: **14 Years**

(Continued)

(21) Appl. No.: **29/277,399**
